UNITED STATES PATENT OFFICE.

HUBERT J. LA JOIE, OF NEW YORK, N. Y., ASSIGNOR TO AUTO PNEUMATIC ACTION COMPANY, OF NEW YORK, N. Y., A CORPORATION OF NEW YORK.

MECHANISM FOR CONTROLLING THE DYNAMICS OF PNEUMATICALLY-OPERATED MUSICAL INSTRUMENTS.

Application filed August 12, 1925. Serial No. 49,739.

The object of this invention is to provide a new and improved mechanism for controlling the dynamics of pneumatically operated musical instruments.

- 5 To this end the invention consists in using a governed tension in the setting pneumatics and in a novel mechanical connection between the setting pneumatics and the governing valve.
- 10 The invention will be best understood by a detailed description of the specific apparatus illustrated in the accompanying four sheets of drawings, which illustrate the best form of apparatus now known to me for practicing my invention.

In the drawings,

Fig. 1 is a bottom plan view of a grand player piano showing my improved controlling mechanism applied thereto;

20 Fig. 2 is a plan on an enlarged scale of the mechanism for controlling the dynamics;

Fig. 3 is an end view thereof, looking in the direction of the arrow 3 in Fig. 2;

25 Fig. 4 is a side view thereof, looking in the direction of the arrow 4 in Fig. 2;

Fig. 5 is a section on the line 5—5 of Fig. 2, showing the valve chest and governor for the same;

30 Fig. 6 is an enlarged sectional view on the line 6—6 of Fig. 2, showing the valve chest and one of the setting pneumatics;

Fig. 7 is an enlarged transverse sectional view through the governor showing the connection to the governing valve; and

35 Fig. 8 is a diagrammatic view showing the music sheet, tracker and connections to the mechanism for controlling the dynamics.

Referring to the drawings and in detail, it will be seen that I have illustrated my 40 invention as applied to a grand player piano. A designates the tracker, which together with the music sheet controlling mechanism may be arranged in a drawer sliding under the keys. B designates the action pneumatics which may be secured to the bottom of the piano. C designates the suction producing pump which may be secured to the bottom of the piano bed and which may be driven by a suitable motor. A conduit D extends from the pump to a block E arranged on the improved controlling mechanism. The controlling mechanism has a governing pneumatic F, the movable leaf of which has a passage which connects to

the block E, and which movable leaf carries a valve seat G having a laterally opening passageway. This passageway is controlled by a governing valve H, pivoted to the valve seat G, and held against the same by a spring I. It will be seen that the valve H 55 co-operates with the valve seat G so as to work practically as a knife edged valve, whereby the adjustments hereinafter referred to can be made very accurately.

A valve chest J is mounted on top of the 60 mechanism. A conduit K extends from the block E to a governor L, consisting of a pneumatic L', spring L² and valve L³ constructed in any approved form, such for example as illustrated in Fig. 5. This governor connects to said valve chest and by using the same a governing tension will always be present in the valve chest while the instrument is in operation.

A series of setting pneumatics is arranged 65 on top of the valve chest. This series may be made up of any desired number, four, P', P², P³ and P⁴ being illustrated in the present embodiment of the invention. These setting pneumatics are controlled by primary valves Q arranged in the valve chest, which primary valves are connected by tubes T', T², T³ and T⁴ to openings 1, 2, 3 and 4 in the tracker. The governing pneumatic F is normally pulled to open position by a 80 spring U.

A walking beam W is mounted on top of the controlling apparatus. This walking beam is shown in plan in Fig. 2. The same consists of a rod or wire bent to have two 90 bearing sections 10—10, arms extending therefrom which carry a straight section 11 and an extending operating arm 12. A link 13 is connected to the arm 12 and adjustably connected to a rod 14 extending 95 into the governing pneumatic F and connected to the pivoted governing valve H. The portion or section 11 of the walking beam is normally held in raised position by a spring R. Arms S extend from the movable wings of the setting pneumatics and have pieces of felt on the under sides thereof, so that the arms can engage softly with the straight section 11 of the walking beam W. Adjustable stops S', S², S³ and S⁴ are 100 arranged to co-operate with these arms S and to adjust the collapsing action of the setting pneumatics P', P², P³, and P⁴ so that

the series will have different throws, these throws being progressively arranged. The pneumatics P' and P^2 may be made smaller than the pneumatics P^3 and P^4 , if desired.

- 5 By this arrangement the pneumatic P' will lift the governing valve H a certain distance, the pneumatic P^2 a further distance, the pneumatic P^3 a further distance, and the pneumatic P^4 a still further distance. By 10 adjusting the stops S' , S^2 , S^3 and S^4 these throws may be varied so that four increasing openings of the valve seat G can be obtained. This gives a device by which five tensions can be obtained, namely the normal tension 15 when none of the setting pneumatics is called into operation, and in addition any one of the settings obtained by any one of the four setting pneumatics. These tensions can be adjusted so that a progressive series 20 of tensions is available for the action pneumatics.

By the arrangements described, these tensions will be applied according to the cutting of the music sheet and thus the dynamics of the playing of a piece of music can be controlled. By continuously changing from one tension to another by the perforations in the music sheet, a very beautiful rendition of the piece of music can be obtained. The 25 pneumatics operating the hammer rail sections and the pneumatic operating the loud pedal may also be controlled from the valve chest.

By using a governed tension in the valve 30 chest the adjustments will very easily take place and by using the walking beam construction previously described the adjustments will be powerfully and positively made.

The details and arrangements herein shown and described may be greatly varied by a skilled mechanic without departing from the scope of my invention as expressed in the claims.

Having thus fully described my invention 45 what I claim and desire to secure by Letters Patent is:—

1. In a mechanism for controlling the dynamics of a pneumatically operated musical instrument, the combination of the action pneumatics and tracker, a pump, a tension controlling device consisting of a governing pneumatic, spring and governing valve, and means to set the governing valve positively to different positions consisting of a valve 50 chest, a series of setting pneumatics connected thereto, primary valves for the setting pneumatics, tubes extending from the tracker to the primary valves, connections from the setting pneumatics to the governing valve, a 55 conduit extending from the valve chest to the pump, and a governor for controlling the tension in the valve chest.

2. In a mechanism for controlling the dynamics of a pneumatically operated musical 60 instrument, the combination of the action pneumatics and tracker, a pump, and a tension controlling device consisting of a governing pneumatic, spring and governing valve, and means to set the valve to different 65 positions consisting of a series of setting pneumatics having different throws controlled from openings in the tracker and a walking beam connected to the valve and operated by said setting pneumatics.

In testimony whereof I have hereunto affixed my signature.

HUBERT J. LA JOIE.
